BASCULE BRIDGE

Leonard O. Hopkins, Nashville, Tenn.

Application December 24, 1934, Serial No. 759,110

6 Claims. (Cl. 14—36)

This invention relates to bridge construction and more particularly to movable bridges of the bascule type.

In the erection of bridges of the aforementioned type it has been necessary to exercise extreme care in positioning the machinery supports and main trunnions so that there will be no misalignment and so that the connecting mechanism between the machinery and the main trunnions will properly engage.

It is an object of the invention to provide a construction wherein small inaccuracies in the positioning and erection of the parts may be compensated for and yet the means forming a connection between the main trunnions and machinery may be properly maintained in engagement.

Figure 1 is a side elevation of a bridge, embodying my invention;

Figure 2, a view in elevation partly in section of the operating machinery and a portion of the bridge partly in cross section;

Figure 3, a plan view of the link connecting the main trunnion to the machinery support;

Figure 4, a transverse view in elevation of the bridge on line 4—4 of Figure 1; and

Figure 5, a diagrammatic view of the machinery support triangle.

In the drawings reference character 10 indicates a supporting base of any suitable material and form having the pedestals 11 mounted on each side in any suitable manner. Numeral 12 indicates the main trunnions of the bridge which are in alignment and rotatably mounted in the pedestals 11 and extend through and are fixed to the girders 13 which form the outside faces of the bridge leaf member.

The rear portions of the girders 13 are provided with a suitable counterweight 14 mounted thereon. The girders 13 also serve as supports for the longitudinal members 15. A plurality of I-beams 16 are secured in position and serve to support additional longitudinal members 51. The members 15 and 51 support a bridge covering 47 formed of plank or any other suitable material and which may be surfaced by any suitable surfacing material 49 and provided with the curbs 17. The inner ends of the trunnions 12 are supported by girders 18 and extend therethrough. The extending portions form bearing shafts 19 for the connecting link 20 which will be later described.

Suitable transverse plates 22 are mounted between the girders 13 and serve as supports for

the ends of the I-beams 16 and to hold the girders 18 in fixed position.

Referring particularly to Figure 3, a supporting member 45 is mounted on the main base 10 and is provided with upstanding members 23. A shaft 24 having a segmental rack 25 fixed thereto is rotatably mounted in the members 23. The upper edge 21 of the rack 25 rests against and is secured to a girder 26 which is secured by any suitable means between the plates 22. The other edge of the rack 25 is supported by a beam 27 which is mounted between the girders 18 and which in turn is supported and reinforced by the I-beam 28 secured to the framework in like manner. The teeth of the rack 25 are in mesh with the teeth of a pinion gear 29 keyed on a shaft 30 which is rotatably mounted in a machinery support formed by upright members 31 and the beams 46.

The lower end of the machinery support is pivoted on a shaft 32 supported by bearing lugs 33 which are secured in any suitable manner to the main base 10. The main drive shaft 34 is rotatably mounted in the supports 31 and is driven by any suitable driving means indicated by numeral 35 and being mounted on the base 36. A suitable gear train is provided consisting of a gear 37 mounted on the shaft 34 meshing with a gear 38 on a shaft 39 which operates a pinion gear 40 keyed to the shaft 39. The gear 40 in rotating the shaft 39 causes the gear 41 to rotate the shaft 30 and hence the main driving pinion 29 which is fixed thereon. A coupling 42 is mounted on the shaft 34 which may be connected with suitable standby or emergency operating mechanism which may be actuated by hand or by any other suitable means.

A connecting link 20 is rotatably mounted on the inner ends 19 of the trunnions 12 and consists of a flat member 43 having its outer corners 44 which extend to each side of the machinery support, rotatably mounted on the ends of the shaft 30. This link 20 serves to prevent the shaft 30 and the gears mounted thereon from being displaced relative to the main trunnions 12 and prevents disengagement of the main drive pinion 29 and the rack 25. The connecting link 20 extends through an opening in the rack 25 and is provided with a cut-out portion 48 which allows the rack 25 to move up and down to raise and lower the leaf member.

A supporting member 50 is provided on the base 10 and serves as a stop bearing or support for the leaf when the bridge is in horizontal or closed position as shown in Fig. 2.

The operation of the bridge is apparent since the movement of the leaf member from closed to open position, or vice versa, is accomplished by rotation of the main pinion gear 29 which in turn rotates the rack 25 which is rigidly secured to the leaf member. The gear 29 is powered by any suitable driving means through a system of gearing as above described.

It will be readily apparent that the pivot 32 permits the machinery support to be moved so that the pinion 29 may be initially properly engaged with rack 25 regardless of small inaccuracies in the relative positioning of the machinery support bearings 36 and the main trunnions. Further, when the link 20 is in position it so connects the main trunnions and the shaft 30 that this proper engagement may always be maintained and yet the pivotal point 32 of the machinery support may be varied.

20 A study of the diagram in Figure 5 will clearly bring out this feature. Point A indicates the main trunnion 12 of the bridge which serves as the axis or fixed point of the machinery support triangle. B indicates the shaft 30 and *a* the connecting link 20. Reference character C indicates the pivotal point of the machinery support and *b* a fixed distance between the shafts 30 and 32 as determined by supports 31 and beams 46. The side *c* is variable and it may be clearly seen 30 from this diagram that the side *c* may be varied without affecting in any way the adjustment of the operating parts, since the distances *a* and *b* are always of predetermined lengths.

The advantages derived from this particular 35 construction results in a saving in that it is possible to erect the machinery in a way that it will not be out of alignment or adjustment, thereby making it possible to reduce the amount of skilled labor necessary in its construction and 40 erection. The simplicity and compactness necessarily reduces cost in materials and results in a bridge that is easily maintained after being erected.

The particular type of bascule bridge shown 45 in the drawings is a highway structure, a double-leaf being shown merely for the purposes of description. This showing is but typical of the many types to which the features may be applied. It is not intended that the invention be limited 50 to any particular form of bascule bridge or foundation.

It will be obvious to those skilled in the art 55 that various changes may be made in my device without departing from the spirit of the invention and therefore I do not limit myself to what is shown in the drawings and described in the specification, but only as indicated by the appended claims. For example, it is apparent that the link 20 may be connected at other points 60 than to the trunnions 12, as for instance to a point on the leaf which is in alinement with the centerline of the trunnions.

Having thus fully described my said invention, what I claim as new and desire to secure by 65 Letters Patent, is:

1. A bridge of the kind described comprising a

base, a bridge leaf pivotally mounted on said base, a rack secured to said bridge leaf, a support pivotally mounted adjacent said rack and having a system of gears mounted therein in operative relation with said rack, means connected between said support and the pivotal axis of said leaf for maintaining them in operative position.

2. A bridge of the kind described comprising a base, a bridge leaf having trunnions secured thereto being pivotally mounted on said base, a rack secured to said bridge leaf, a machinery support pivotally mounted on said base adjacent said rack and having a system of gearing therein, a link connecting the upper portion of said machinery support and said trunnions whereby the operative connection between said gearing and said rack is maintained upon change of position of the pivotal point of said machinery support.

3. A bridge of the kind described comprising a base having supports mounted thereon, a bridge leaf having trunnions secured thereto for mounting said leaf in said supports, a rack secured to said bridge leaf, a machinery support pivotally mounted on the base adjacent said rack, a system of gearing positioned therein, means for driving said gearing and a link member connecting and maintaining said rack and gearing in operative relation whereupon shifting of the pivotal point of the machinery support does not affect the engagement of said rack and gearing.

4. A bridge of the kind described comprising a base having supports mounted thereon, a bridge leaf member having trunnions fixed thereto and adapted to pivotally mount said member in said supports, a machinery support pivotally mounted in close proximity to the inner ends of said trunnions, a train of gears mounted in fixed relation in said support, a rack secured to the leaf member and adapted to engage and be driven by said train of gears, and means connecting the said machinery support and said inner ends of the trunnions for maintaining the rack and gears in operative position upon shifting of the pivotal axis of the machinery support.

5. In a bascule bridge, a bridge leaf, a rack secured to said bridge leaf, a gear train operatively connected to said rack for moving said bridge leaf, with said gear train secured to a support and being bodily movable to compensate for minor inaccuracies in positioning of itself or said rack, and means for holding said gear train in operative relation to said rack irrespective of such compensating movement.

6. In a bridge of the kind described, a base, trunnions rotatably supported on said base, a bridge leaf secured to said trunnions, a drive pinion, means for rotating said pinion, a gear train having an operative connection with said pinion and said trunnions for transmitting rotary motion to the latter, said gear train being movable bodily as a unit to compensate for minor inaccuracies in positioning of itself or said trunnions, and means for holding said gear train in operative relation to said trunnions irrespective of such compensating movement.

LEONARD O. HOPKINS.
